Primary Examiner—Wallace R. Burke**Assistant Examiner—Marcus Jackson****Attorney, Agent, or Firm—Leon Gilden****[57] CLAIM**

The ornamental design for a audible alarm for detecting earthquakes and gas leakage, as shown and described.

DESCRIPTION

FIG. 1 is a front elevational view of the audible alarm for detecting earthquakes and gas leakage showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

FIG. 1

FIG. 2

FIG. 3

FIG. 4
